(57) CLAIM

The ornamental design for a tablet dispenser, as shown and described.

DESCRIPTION

FIG. 1 is a perspective view of a tablet dispenser;
FIG. 2 is a front side view of the tablet dispenser shown in FIG. 1;

FIG. 3 is a right side view of the tablet dispenser shown in FIGS. 1 and 2;

FIG. 4 is a top side view of the tablet dispenser shown in FIGS. 1-3;

FIG. 5 is a back side view of the tablet dispenser shown in FIGS. 1-4;

FIG. 6 is a left side view of the tablet dispenser shown in FIGS. 1-5; and,

FIG. 7 is a bottom side view of the tablet dispenser shown in FIGS. 1-6.

The dashed lines are shown in the views for illustrative purposes only and form no part of the claimed design.
